HENRY J. GAYLORD, OF SYRACUSE, NEW YORK

TEMPORARY BINDER FOR PAMPHLETS AND OTHER FOLDED ARTICLES

Application filed November 15, 1930. Serial No. 495,912.

This invention relates to a temporary binder for pamphlets and other folded articles in which one or more supporting bars are engaged in the folds of a corresponding number of pamphlets, and refers more particularly to the means for locking and releasing these bars in and from their holding positions.

One or more of these bars is or are hinged at one end to the corresponding end of a channel bar to swing into and out of the channel, and each is adapted to enter the fold of the pamphlet or other folded article to retain the same in the channel bar against accidental displacement, and the main object of the present invention is to provide the other end of the channel bar with simple and efficient key-controlled means for locking the pamphlet-supporting bars with the pamphlets thereon in the channel of the channel bar, and also to permit the locking means to be easily and quickly released by the insertion of the key so that any one or all of the pamphlets may be removed from their respective bars and replaced by others if desired.

Other objects and uses relating to specific parts of the binder will be brought out in the following description.

In the drawings:

Figure 1 is a perspective view of an open binder embodying the various features of my invention.

Figure 2 is a longitudinal vertical sectional view, partly broken away, taken in the plane of line 2-2, Figure 1.

Figures 3 and 4 are transverse vertical sectional views taken respectively in the planes of lines 3-3 and 4-4, Figure 2.

Figure 5 is a sectional perspective view of the interior of one end of the binder, omitting the covers, in which the pamphlet-supporting bars and locking means therefor are shown in their locked positions.

Figure 6 is a face view of the key for releasing the bar-locking mechanism.

Figure 7 is a horizontal sectional view through one end of the binder, taken in the plane of line 7-7, Figure 2.

As illustrated this binder comprises a sheet

metal channel-bar —1— of any suitable length or width capable of receiving one or more pamphlets or other folded articles of predetermined dimensions, said channel bar being provided with a flat lengthwise bottom wall —2— and opposite upright side walls —3— extending along opposite edges of the bottom wall in parallel spaced relation.

Suitable covers —4— are hingedly secured in any suitable manner to the upper longitudinal edges of the side walls —3— for enclosing and protecting the pamphlets or other folded articles which may be supported in the channel-bar —1— upon the lengthwise bars presently described.

The opposite ends of the upper portions of the side walls —3— of the channel-bar —1— are connected by cross pins —5— and —6— in parallel spaced relation some distance above the bottom wall —2— for receiving and supporting, respectively (one or more, in this instance three, lock-bars —7—, and an angular lock-plate —8—.

That is, the lock-bars —7— are pivotally mounted side by side upon the cross pin —5— near one end of the channel bar to swing vertically into and out of the channel lengthwise thereof and extend from the pivot —5— to points of proximity to the other end of the channel bar, but are of appreciably less length than the channel bar to permit the free operation of the lock plate —8— to and from its locking position when released, in a manner hereinafter described.

The angle plate —8— is hinged near its angle to the cross pin —6— with the open side of the angle facing inwardly, the arms as —9— and —10— of the angle plate being disposed at substantially right angles to each other and in such manner that when in its locking position the arm —9— will extend downwardly from the pivot —6—, while the other arm —10— will extend inwardly across and directly over the adjacent ends of the lock-bars —7— for holding the lock-bars —7— with the folded articles thereon against accidental displacement from the channel of the bar —1—.

The means for locking the angular plate or bell-crank-lever —8— in its holding position

consists, in this instance, of a flat spring detent —11— secured by rivets —12—, or equivalent fastening means to the bottom of the channel-bar —1— to extend transversely 5 across the channel approximately the full width thereof between the side walls —3—, as shown more clearly in Figures 4 and 5.

The free end of the spring-detent —11— is normally tensioned upwardly in spaced relation to the adjacent portion of the bottom 10 wall of the channel-bar —1— and terminates almost directly under the axis of the pivotal pin —6— so that it may normally lie in the path of movement of the lower edge of the 15 arm —9— of the lock-plate —8— for engaging said arm and holding the lock-plate in position for locking the adjacent ends of the lock-bars —7— against undue upward swinging movement.

20 Suitable means is provided for producing an audible click when the lock-plate —8— is forced into locking engagement with the adjacent end of the spring detent —11— and for this purpose the pendant arm —9— of the 25 lock-plate —8— is provided with an inwardly projecting shoulder or stop —13— adapted to be engaged by the free end of the detent —11— after the lower edge of the arm —9— has been moved beyond the free edge of the 30 detent, as shown in Figures 2 and 5.

The free end of the detent —11— is adapted to be tripped from holding engagement with the lower edge of the arm —9— by means of a tapered key —14—, shown by 35 full lines in Figure 6 and by dotted lines in Figure 2, and in order that the insertion of the key endwise may properly function for tripping the detent, the adjacent end of the bottom wall —2— of the channel bar —1— 40 is bent upwardly at substantially right angles thereto to form a rigid end wall —15— having a keyhole or slot —16— through which the tapered end of the key —14— is adapted to be inserted from the outside inwardly.

45 This end wall —15— is arranged closely adjacent the outer face of the pendant arm —9— of the lock-plate —8— to limit the outward swinging movement of said arm in addition to its main function of forming a guide 50 for the key —14—.

The pendant arm —9— of the lock-plate —8— is also provided with a keyhole or slot —17— registering with the slot —16— when said plate is in its locking position, as shown 55 in Figure 2, said slot —17— being open at the bottom to allow the lock-plate to swing from its locking position, shown by full lines in Figure 2, to its released position, shown by dotted lines in the same figure, while the 60 key —14— is still in position for tripping the detent —11—.

It will be noted upon reference to Figure 2, that the free ends of the lock-bars —7— terminate a sufficient distance from the arc of 65 movement of the free edge of the pendant

arm —9— of the lock plate —8— to allow said plate, when released, to swing from its locking position to its released position without friction with the adjacent ends of the lock-bars —7—.

The keyholes or slots —16— and —17— in the end wall —15— and pendant arm —9— are preferably arranged midway between the opposite side walls —3— of the channel-bar —1—, while the stop shoulder —13— 75 on the pendant arm —9— is arranged at one side of the slot —17— to avoid interference with the free insertion and removal of the key —14—.

It is, of course, understood that the lock-bars —7— will be free to slide axially upon their pivotal pin —5— and may, therefore, be arranged in normally spaced relation to accommodate pamphlets or other folders of different thicknesses.

The free extremities of the two outer lock-bars —7— are preferably offset or deflected laterally at —18—, as shown in Figure 7, to afford a relatively broad bearing against the underside of the overhanging arm —10— of the lock-plate when the bars —7— are engaged in the folds of the pamphlets or other folders to hold the latter in the channel of the bar —1—, said offset portions also serving to prevent undue sliding of the folded articles from the free ends of the lock-bars —7— when withdrawing or replacing one or more of the pamphlets from or upon the lock-bars.

The channel-bar —1—, lock-bars —7—, lock-plate —8—, spring detent —11— and key —14— are all preferably made of comparatively thin sheet metal, while the covers —4— may be made of cloth-covered cardboard or other comparatively inexpensive material so that the entire binder may be made and sold at a comparatively low cost.

Operation

When the lock-bars —7— with the pamphlets or folders thereon and the lock-plate —8— are in their locking positions, as shown more clearly by full lines in Figure 2, and it is desired to remove one or more of the pamphlets from their corresponding bars —7—, the tapered key —14— will be inserted through the registering slots —17— and —16— with its tapered edge in sliding engagement with the top wall of the slot —16— and its lower edge engaged with the free end of the spring detent —11—, thereby forcing said detent downwardly against its tension below the lower edge of the pendant arm —9— of the lock-plate —8—, thus permitting the lock-plate to be swung by hand about its pivot —6— to the position shown by dotted lines in Fig. 2, whereupon any one or more of the pamphlets and its supporting bar —7— may be rocked upwardly about the pivotal pin —5— out of 130

the channel of the channel-bar —1— to enable said pamphlet or pamphlets to be withdrawn endwise from the free end of its supporting bar which may be re-engaged in the fold of another pamphlet or folder if desired, displacement and replacement of the folder upon any one of the bars —7— being effected without disturbing the folders on the other bars.

10 When the pamphlets are properly mounted upon their respective bars —7— the latter with the pamphlets thereon are swung into the channel of the bar —1— to rest upon the detent —11— in the bottom thereof.

15 The key —14— having been withdrawn, the lock plate —8— is then returned by hand to its locking position, thereby causing the lower edge of the arm —9— to ride lengthwise of and upon the upper surface of the detent —11— to depress the same against its own tension until the lower edge of the arm —9— passes beyond the outer edge of the detent which then snaps into engagement with the stop shoulder —13— and adjacent inner face of the arm —9— with an audible click to indicate that the lock-plate —8— has reached its locking position, under which conditions the upper arm —10— of the lock-plate —8— will overhang the adjacent ends of the lock-bars —7— to hold the latter with the pamphlets thereon against upward displacement from the channel-bar.

20 The construction shown and described is particularly simple, practical and efficient for expeditiously binding and releasing pamphlets and other folded articles, but obviously various changes may be made in the details thereof without departing from the spirit of the invention.

25 What I claim is:—

1. In a temporary binder for pamphlets and other folded articles, a channel-bar adapted to receive the folded edges of said articles, a lock-bar hinged at one end to one end of the channel-bar and adapted to swing into and out of the channel and adapted to enter the fold of an article to hold the fold in the channel, an angular lock-plate hinged adjacent its angle to the other end of the channel-bar and having one end movable to and from a position across said channel directly over the adjacent end of the lock-bar, and a key-controlled detent for engaging the other end of the lock-plate for holding the latter in its locking position.

2. In a temporary binder for pamphlets and other folded articles, a channel-bar adapted to receive the folded edges of said articles, a lock-bar hinged at one end to one end of the channel-bar and adapted to swing into and out of the channel and adapted to enter the fold of an article to hold the fold in the channel, an angular lock plate hinged adjacent its angle to the other end of the channel-bar having one end adapted to swing

to and from a position directly over the adjacent end of the lock-bar and its other end movable in the channel, and a spring detent movable into and out of engagement with said other end of the lock-plate for locking 70 and releasing said lock-plate in and from its holding position, said channel-bar having an end plate at the adjacent end of the lock bar, the end-plate and said other end of the lock-plate having registering slots for receiving 75 a key by which the detent may be tripped from its holding position.

In witness whereof I have hereunto set my hand this 10th day of November 1930.
